UNITED STATES PATENT OFFICE.

RICHARD DEIGHTON, OF SHAWNEE MOUND, MISSOURI.

CHURN.

SPECIFICATION forming part of Letters Patent No. 367,603, dated August 2, 1887.

Application filed April 26, 1887. Serial No. 236,186. (No model.)

To all whom it may concern:

Be it known that I, RICHARD DEIGHTON, of Shawnee Mound, in the county of Henry and State of Missouri, have invented a new and Improved Churn, of which the following is a full, clear, and exact description.

The object of the invention is to provide a churn which can be given either a rotary or a rocking motion to effect the separation of the butter, and which churn can be readily removed from its frame to be cleaned and aired, and as readily secured in the frame when again required for use.

The invention consists in the construction of the various parts and combinations of the same, as will be hereinafter fully described and claimed.

Reference is to be had to the accompanying drawings, forming a part of this specification, in which similar letters of reference indicate corresponding parts in all the figures.

Figure 1 is a side elevation of a churn constructed in accordance with my invention. Fig. 2 is a like elevation at right angles to Fig. 1. Fig. 3 is a plan view, parts being broken away. Fig. 4 is a perspective view of the rocking arm of the churn; and Fig. 5 is an enlarged view of a section of the clamp-band, showing the connection therewith of the packings or cushions.

The supporting-frame of the churn consists of the oppositely-inclined legs *a a* and *b b*, the opposite legs being hinged together near the top by hinges *c* and braced near the bottom by braces *d d*. The braces *d d* are formed trough-shaped, their back pieces being nailed or otherwise fastened on the outside of the legs *a a* and *b b*, respectively, and the portions *d' d'* of the said braces fitting between the said legs and extending across from one leg to the other, their ends bearing against the inner sides of said legs. The legs *a a* and *b b* are further braced by rods or bolts *e*, (shown in dotted lines in Fig. 3,) that pass from one leg *a* to the other, and from one leg *b* to the other, beneath or within the trough-shaped braces *d*. On the ends of the bolts *e* are screwed the nuts *f*.

Above the hinges *c* the inclined legs are chamfered, so as to come close together at the upper ends when the lower ends are swung outward, and eyebolts or pins *g*, passed through the said chamfered ends, firmly hold the frame

in the upright position. Upon withdrawing the pins *g* the frame may be folded together, and will occupy but little space until again required for use.

The churn *h*, made of glass or other vitreous substance or of metal, is held in the supporting-frame by the two-part circular clamp-band *i* and the frame *j j*, suspended from said clamp-band, the short journals *i' i'* being formed upon or secured to the clamp-band and having bearings in the upper ends of the legs of the supporting-frame above the hinges *c* thereof. The members of the frame *j j* are suspended from the clamp-band *i* by means of pins *j'*, that pass through the said clamp-band and into or through apertures *j''* in the frame *j*. Two sets of these apertures *j''* are formed in the frame *j*, one above the other, for a purpose hereinafter to be specified. The members of the two-part clamp-band *i* are formed at their ends with or have secured to them corresponding lugs *k k*, into which take the screw-bolts *l l*, and the tightening of which bolts *l* causes the said clamp-band to firmly grasp the churn around the body, the bottom of the churn resting in the frame *j j*. The heads *l'* and nuts *l''* of the screw-bolts *l* are each made rounded on their inner or bearing-surfaces.

The neck of the churn is formed with an internal flange, *h'*, on which is raised an annular bead, *h''*, against which bead *h''* bears a packing-ring, *m*, secured to the under side of the churn-cover *n*. The churn-cover *n* is fastened in place by a bar, *o*, which is secured to said cover and projects outward at each side thereof. The threaded upper ends of rods *p p* pass upward through the bar *o*, the lower hooked ends of said rods grasping the bolts *l* of clamp-band *i*. On the said upper ends of the rods *p p* are screwed wing-nuts *q q*, the screwing down of which presses the bar *o* downward and with it the cover *n* of the churn, causing the packing-ring *m* on the bottom of said cover to bear tightly on the bead *h''* on the internal flange of the neck of the churn, which effectively prevents leakage during the operation of churning.

On the inner side of the clamp-band *i* are secured at intervals pieces *r*, of rubber or leather, to form a cushion between the said clamp-band and the churn to prevent injury to the latter, and at the same time affording

the clamp-band a better grasp on the churn than it would otherwise have. These pieces *r* are riveted to the clamp-band *i* by rivets *s*, Fig. 5, the heads of which rivets are beveled 5 on the under side so that the said rivets will embed themselves in the pieces of rubber or leather flush with the surface thereof.

When it is desired to effect the churning by a rotary motion of the churn, the crank-handle 10 *t* is employed, it being formed to fit the squared projecting end of one of the journals *i'* of the clamp-band *i*.

Should it be desired to effect the churning by a rocking motion of the churn, the latter 15 is lowered by disengaging the lower set of apertures *j'* of frame *j* from the pins *j*', and lowering the said frame *j* till the upper set of apertures *j'* therein come opposite the pins *j*', in which lowered position the frame *j* is 20 then secured. The crank-handle *t* having been removed, the rocking handle *u* is substituted, whereby a rocking motion may be imparted to the churn with but little exertion on the part of the operator.

25 The dotted lines in Fig. 2 indicate the churn in the lowered position, and with the rocking handle *u* secured in place. An aperture, which is closed by a plug or cork, *v*, is formed in the cover *n* of the churn for the purpose of ventilation and for taking observations during the 30 operation of churning.

With a churn and frame-work constructed as above described, when it is not required for use the churn may be removed from its 35 frame and the latter taken apart and laid aside, occupying but little space, and may be again erected with very little trouble. The churn, too, may be quickly removed from its frame for cleaning and airing.

40 If desired, the ordinary wooden churn may be substituted for the churn *h* by placing a packing-ring beneath the cover.

Having thus fully described my invention, what I claim as new, and desire to secure by 45 Letters Patent, is—

1. The two-part clamp-band *i*, having lugs *k* and journals *i'*, and the suspended frame *j j'*, in combination with the churn *h* and a supporting-frame in which the journals *i'* have a bearing, substantially as described. 50

2. The combination, with the churn *h*, of the two-part clamp-band *i*, having lugs *k* and journals *i'*, a supporting-frame in which the said journals revolve, and the bolt *l* for clamping the lugs or ears *k*, substantially as described. 55

3. The two-part clamp-band *i*, having lugs *k*, and the screw-bolts *l*, taking into said lugs, in combination with the churn *h* and its cover, the bar *o*, rods *p*, connecting the bar *o* and the 60 bolts *l* and nuts *q*, all arranged substantially as shown and described.

4. The two-part clamp-band *i*, having journals *i'* and lugs *k*, in combination with the churn *h* and its cover, and the bolts *l* and cushions *r*, the said cushions being riveted to the 65 said clamp-band by means of the rivets *s*, the heads of which rivets are beveled on their under sides, substantially as shown and described. 70

5. The two-part clamp-band *i*, having journals *i'*, the suspended frame *j j'*, and mechanism for vertically adjusting the frame *j j'* on said clamp-band, in combination with a supporting-frame in which the journals *i'* have a 75 bearing, substantially as shown and described.

6. The two-part clamp-band *i*, formed with lugs *k* and having short journals *i'*, in combination with the bolts *l* for clamping the lugs *k*, and a supporting-frame in which the said journals have a bearing, the rocking arm *u*, and the churn *h*, substantially as shown and described. 80
